United States Patent Office

Des. 183,803
Patented Oct. 28, 1958

183,803

ELECTRICAL ROLLER VIBRATOR OR SIMILAR ARTICLE

Samuel L. McNair, Whitman, Mass.

Application August 7, 1957, Serial No. 47,260

Term of patent 14 years

(Cl. D83—1)

Fig. 1.

Fig. 2.

Fig. 3.

Fig. 1 is a top plan view,

Fig. 2 is a front elevational view, and

Fig. 3 is an end elevational view of an electrical roller vibrator, embodying my new design.

The bottom surfaces of the vibrator are plain.

I claim:

The ornamental design for an electrical roller vibrator or similar article, substantially as shown and described.
